ABSTRACT

A dispensing apparatus comprising a container and a pump housing carrying a pressure bulb which, when compressed, effects the discharge of a metered quantity of the product to be dispensed through the positive pressure arising in the pressure bulb at this compression and whereby two valves, arranged in the pump housing are displaced. The pump housing is arranged in a narrow portion or neck of the container which neck has a swelling forming the pressure bulb. The container with its neck and pressure bulb are formed in one piece from non-rigid plastic or rubber materials.

DISPENSING APPARATUS

BACKGROUND OF THE INVENTION

The present invention concerns an improved dispensing apparatus for discharging liquid or creamy products this apparatus being of the kind comprising a container and a pump housing arranged at the discharge end, the said pump housing having an internal through passage in which are disposed two valves delimiting between them an intermediate valve chamber being in constant communication with the interior of a resilient pressure ball which is provided on the pump housing and adapted, when compressed, i.e., when a positive pressure is generated therein, to close the valve positioned adjacent the discharge end of the container and open the valve positioned adjacent the discharge end of the through passage, and the reverse at the occurrence of a negative pressure in the pressure bulb.

Such dispensing apparatuses are not very hygienic since they are difficult to clean thoroughly whereby in addition the dispensing capability of the apparatus gradually deteriorates. Because apparatuses of this kind are generally intended to be attached to the end of conventional tubes, flasks, bottles and the like sealing problems always arise. For instance, the product to be dispensed may leak out or outside air be sucked in, resulting in malfunctioning of the apparatus. If air is allowed to enter at a point ahead of the discharge opening of the apparatus, oxidizing of the product will result, inevitably accompanied by blocking or plug-up which might make impossible further discharge of the product. For the above reasons previously known apparatuses of this kind cannot possibly be said to fulfil the demands of sterility required in medical use.

SUMMARY OF THE INVENTION

To eliminate among others the drawbacks referred to above the dispensing apparatus in accordance with the invention is characterized in that at its discharge end, the container is formed with a neck portion in which the pump housing is arranged that the pressure bulb is formed through a swelling of the neck portion and that the container with its neck portion and pressure bulb is manufactured in one piece from non-rigid plastic or rubber materials.

Owing to the low manufacturing costs of producing an apparatus of this kind a disposable dispensing apparatus is provided which is extremely hygienic and may be used to dispense products of various kinds. For domestic uses may be mentioned products such as mustard, liquid soaps, hair schampoos and the like. In the treatment of illnesses, such as eye diseases, the apparatus in accordance with the invention is highly suitable for feeding out liquids for eye baths. In this instance, the discharge opening is preferably shaped as bowl adapted to be pressed against the eye ball. Since the apparatus with its container may be delivered completely sterilized and sealed, it is very useful also for other medical purposes. Because of certain predetermined quantity is dispensed at each compression of the pressure bulb it is also possible to provide for metering of the container contents, such as for instance in dosing of medicines.

BRIEF DESCRIPTION OF THE DRAWINGS

The invention will be described in detail in the following with reference to the accompanying drawings, in which:

FIG. 1 is a lateral view of the apparatus in accordance with the invention,

FIG. 2 is a longitudinal section, shown in a larger scale, of the lower portion of the apparatus,

FIG. 3 is a section through the apparatus along line III-III of FIG. 2, and

FIG. 4 is an exploded view of the lower portion of the apparatus.

DETAILED DESCRIPTION OF A PREFERRED EMBODIMENT

As shown in FIG. 1 the apparatus consists of a container 1 having a neck portion 2 formed at the discharge end. The neck portion is in turn formed with a pressure bulb 3. In the neck portion 2 is formed a pump housing 4 such that the discharge end 5 thereof extends beyond the neck 2. FIG. 1 also shows that the container 1 is closed in air-tight manner. By manufacturing the container from rubber or non-rigid plastic materials, such as polyvinyl chloride, it is easy to compress the container as the product contained therein is being discharged.

The longitudinal section in accordance with FIG. 2 clearly illustrates the manner in which the pump housing 4 is mounted in the neck portion 2 of the container 1. At its lower end, the neck 2 is provided with a circumferentially extending peripheral groove 6 in which engages a flange or bead 7 arranged along the circumference of the pump housing 4. In order that a communication passage 8 (to be described in detail later) in the pump housing 4 be maintained in correct position and brought to communicate with the interior of the pressure bulb 3, a notch 9' formed at the lower edge 9 of the neck 2 is provided in which notch engages a lip 10 on the pump housing 4. The pump housing 4 is provided with a through passage 11 in which are disposed two valves 12 and 13. They define between them an intermediate valve chamber 14 which is in constant communication with the interior of the pressure bulb 3 through the communication channel 8.

The valves 12 and 13 are formed from a tubular body 15, 16 (see also FIG. 4) which is provided with a funnel-shaped rim 17, 18 of a resilient material and so directed that in their position of rest the valves 12, 13 close off valve chamber 14 from the rest of the through passage 11. The radial guidance of the valves 12, 13 is obtained by means of a guide shaft 19 which is positioned in the through passage 11 and extends through the tubular bodies 15, 16 of the valves. The guide shaft 19 is provided at its lower end with a tripod 20 resting against a shoulder 21 in the through passage 11. The shoulder is formed through the stepwise tapering of the through passage 11 towards its discharge end 33. The upper end of the guide shaft 19 abuts against a stop plate 22 which is inserted into the upper end of the pump housing 4 and provided with a diametrically positioned stop pin 23 (see FIG. 3) against which the guide shaft 19 abuts. A supporting sleeve 24 is inserted between the stop plate 22 and the upper valve 12 whereby a support is provided protecting the valve rim

17 when an abnormal pressure is exerted. It also appears from FIGS. 2 and 3 that the pressure bulb 3 is provided with a reinforcing bead 25 facilitating the return movement of the pressure bulb 3 after compression of the latter whereby is ensured the negative pressure necessary for the functioning of the apparatus (as will be described in the following).

FIGS. 2, 3 and 4 also illustrate one embodiment of an attachment means for fastening the apparatus on a wall or the like. A bracket 26 is screwed onto the wall 26, the said bracket being designed to receive the neck portion 2 of the container 1 at that side thereof facing away from the wall. The apparatus is kept in position by means of a clamping plate 28 having a U-shaped cross section, the limbs 29 of said clamping plate embracing the bracket 27, each limb 29 having a pin 30 engaging in a corresponding notch 31 formed in the side of the bracket 27. The clamping plate 28 is provided with an opening 32 for the pressure bulb 3.

In summary, the following takes place in the operation of the apparatus in accordance with the invention, it being assumed that the pressure bulb 3 is not compressed and the interior of the pump housing 4 filled with the product to be discharged. When the pressure bulb 3 is compressed, for instance when squeezed by the thumb of one hand, a positive pressure is generated in the valve chamber 14 whereby the valve rim 17 of the upper valve 12 is being pressed sealingly against the wall of the through passage 11, i.e., the valve 12 closes. At the same time the rim 18 of the lower valve 13 is displaced by the positive pressure of the air contained in the pressure bulb 3. The valve 13 thus also opens and an amount of the product corresponding in volume approximately to the volume of the pressure bulb 3, is being discharged out through the discharge end 33 of the through passage 11. This is so, provided the pressure bulb 3 is completely compressed. If a smaller amount of the product is wanted, naturally the bulb 3 is compressed to a lesser extent. When the compression force on the pressure bulb 3 is then relieved, the bulb tends to resume its original semi-spherical shape, and in doing so it is considerably helped by the reinforcing bead 25. A negative pressure is then created in the pressure bulb 3 and the valve chamber 14, such that the rim 17 of the valve 12 is displaced through the pressure exerted from the mass of the product contained in the container 1. The upper valve 12 thus opens and the lower valve 13 closes under the influence of the negative pressure, the valve chamber 14 filling up with the discharge product. The apparatus is thus again ready to discharge the product upon compression of the pressure bulb 3. It should be noted that the communication channel 8 and the valve chamber 14 are always filled with the product to be discharged, the product being, however, continuously advanced further through the through passage 11. No amount of the product thus remains in any area longer than the period between each use of the apparatus. By suitable dimensioning of the diameter of the discharge end 33 of the through passage 11 in relation to the viscosity of the product to be discharged it is possible, because of the capillary effect, to avoid dripping. When manufacturing the container 1 with its neck portion 2 and pressure bulb 3 as one integral element it is preferable to start from a hose blank of non-rigid plastics which is blown in a mould,

whereupon the upper end of the container 1 is closed by heat sealing. The complete pump housing 4 is thereafter pushed into the neck portion 2 and heat sealing, glueing and the like carried out between the lower edge 9 of the neck portion 2 and the pump housing 4. In many cases it is, however, possible to manufacture the pieces with such excellent fit that the joint is tight also if the above-mentioned measures are not effected.

The invention is by no means limited to the embodiment as shown and described above but several modifications are possible within the scope of the appended claims. For instance the valves 12, 13 may be of a different type than the one shown. They need only fulfil the demand of opening at the present of a positive pressure in the direction away from the container 1 and of closing when a positive pressure is exerted from the discharge end 5 in the direction towards the container 1. The pressure bulb 3 may, for instance, be in the form of torus-shaped bellows extending around the neck portion 2. It is further possible to make the device lockable which is an advantage in cases when it is mounted in public washrooms and the like. The pins 30 are then replaced by a through-screw the head of which is so shaped that the screw may be removed only by means of a special wrench. The discharge end 33 of the through passage 11 may be made closed and being opened, when used, for instance through cutting, and the like.

What I claim is:

1. A dispensing apparatus for discharging a fluid product comprising a container for said fluid product, said container having an elongated neck portion formed integrally therewith, said neck portion having a generally cylindrical configuration with an enlargement protruding outwardly therefrom to define a pressure bulb, said container, neck portion and pressure bulb being made in one piece from a flexible material, a pump housing disposed in said elongated neck portion, said pump housing having an internal central passage having one longitudinal end in communication with said container and the other longitudinal end defining a discharge end, a first and second valve means disposed in spaced relationship to one another in said central passage to define therebetween an intermediate valve chamber, said first valve being located between said container and said intermediate valve chamber, said second valve being located between said intermediate valve chamber and said discharge end, said pump housing having an opening providing communication between said intermediate valve chamber and the interior of said pressure bulb, said pressure bulb being compressible to close said first valve and open said second valve as fluid is forced out of the interior of the pressure bulb, through said pump housing opening and through said pump central passage to said discharge end, said pressure bulb being returnable to its uncom-pressed state to open said first valve and close said second valve as fluid is drawn from said container past said first valve, into said intermediate valve chamber, through said pump housing opening and into the interior of said pressure bulb.

2. A dispensing apparatus according to claim 1 wherein said container, neck portion and pressure bulb are made of non-rigid plastic.

3. A dispensing apparatus according to claim 1 wherein said container, neck portion and pressure bulb are made of rubber.

4. A dispensing apparatus according to claim 2 wherein said non-rigid plastic is polyvinyl chloride. 5
